UNITED STATES PATENT OFFICE.

DAVID M. GILBERT, OF NEW YORK, N. Y.

DESIGN FOR AN INCANDESCENT-LAMP SHADE.

No. 40,141.

Specification for Design.

Patented July 13, 1909.

Application filed March 25, 1909. Serial No. 485,860. Term of patent 7 years.

To all whom it may concern:

Be it known that I, DAVID M. GILBERT, a citizen of the United States, and a resident of the borough of Brooklyn, in the city and State of New York, have invented a new, original, and ornamental Design for an Incandescent-Lamp Shade, of which the following is a specification, reference being had to the accompanying drawing, forming part thereof.

Figure 1 is a side elevation of an incandes-

cent lamp shade showing my new design. Fig. 2 is a plan view of the incandescent lamp shade inverted.

I claim:—

The ornamental design for incandescent lamp shade as shown.

DAVID M. GILBERT.
